UNITED STATES PATENT OFFICE.

CHARLES E. BENTLEY, OF NEW YORK, N. Y.

DESIGN FOR A BOTTLE.

SPECIFICATION forming part of Design No. 20,028, dated July 15, 1890.

Application filed June 3, 1890. Serial No. 354,138. Term of patent 7 years.

To all whom it may concern:

Be it known that I, CHARLES E. BENTLEY, a citizen of the United States, residing at the city of New York, county and State of New York, have invented and produced a new and original Design for a Bottle, of which the following is a specification, reference being had to the accompanying drawing, forming part thereof, and in which the bottle is shown in one perspective view, which fully illustrates the design.

The leading feature of my design for a bottle consists, mainly, in the peculiar form of its lower body portion, which is surmounted by a comparatively long neck or stem, as hereinafter more fully described.

The body portion A of the bottle or ornament has the appearance of being turned in a lathe in circular outline, and is largest in diameter about at its central portion, where it has a corner outline 1, from which the

sides of the bottle curve inward and upward in concaved lines 2 to the neck or stem a, which may be cylindrical or have like diameter throughout, but is shown enlarged toward its upper end. From the corner-line 1 the sides of the bottle curve downward and inward in vertically-convexed outlines 3 to the base or bottom 4. Near the circumferential corner 1 the body of the bottle is provided in its convexed lower surface 3 with a circumferential groove or concavity 5, all as clearly shown in the drawing.

An ordinary cut-glass stopper is represented in the neck or stem of the bottle. 35

I claim as my invention—

The design for a bottle, substantially as herein shown and described.

CHARLES E. BENTLEY.
